[57] **CLAIM**

The ornamental design for a caster wheel brake, as
shown and described.

DESCRIPTION

FIG. 1 is a front perspective view of a caster wheel
brake showing our new design;

FIG. 2 is an enlarged front perspective view thereof;
FIG. 3 is a top, partially in perspective view thereof at
a reduced scale;

FIG. 4 is a bottom, partially in perspective view
thereof;

FIG. 5 is an enlarged left side elevational view thereof;

FIG. 6 is a right side elevational view thereof;

FIG. 7 is a front, partially in perspective view thereof;
and,

FIG. 8 is a rear, partially in perspective view thereof.
The broken line showing of a caster wheel is for illustra-
tive purposes only and forms no part of the claimed
design.

FIG. 1

FIG. 2
